UNITED STATES PATENT OFFICE.

FREDRICK MORGESTERN, OF ALLEGHENY, PENNSYLVANIA.

OVERSHOE-HOLDER.

SPECIFICATION forming part of Letters Patent No. 636,545, dated November 7, 1899.

Application filed April 28, 1899. Serial No. 714,485. (No model.)

To all whom it may concern:

Be it known that I, FREDRICK MORGESTERN, a citizen of the United States of America, residing at Allegheny, in the county of

5 Allegheny and State of Pennsylvania, have invented certain new and useful Improvements in Overshoe-Holders, of which the following is a specification, reference being had therein to the accompanying drawings.

10 The herein-described invention relates to certain new and useful improvements in boots and shoes, and more particularly to attachments for overshoes that will prevent the same from coming off.

15 The invention has for its object to construct a device of this character that may be easily attached to rubbers and overshoes; furthermore, one that can be adjusted to fit various sizes of shoes.

20 The invention contemplates to construct a device of the above-referred-to class that will automatically clamp itself to the heel of a shoe and provide simple and effective releasing mechanism when it is desired to re-25 move the same.

With the above and other objects in view my invention finally consists in the novel construction, combination, and arrangement of parts to be hereinafter more fully described, 30 and specifically pointed out in the claim.

In describing the invention in detail reference is had to the accompanying drawings, forming a part of this specification, wherein like numerals of reference indicate corresponding parts throughout the several views 35 thereof, and in which—

Figure 1 is a vertical sectional view of an overshoe partly cut away, illustrating in dotted lines a shoe with my improvement attached thereto. Fig. 2 is a perspective view of the attachment. Fig. 3 is a perspective view of the clamp. Fig. 4 is an inverted perspective view of the same. Fig. 5 is a detail view in perspective of the rear portion of the 45 heel-plate. Fig. 6 is a detail view of the end of the releasing-lever.

In the drawings the reference-numeral 1 indicates a shoe, (shown in dotted lines of Fig. 1 of the drawings,) and 2 represents a 50 rubber shoe, in the heel of which is secured by suitable fastening means a heel-plate 3. Centrally arranged upon this said plate at the

rear thereof is an upwardly-extending spring portion 4, said upwardly-extending spring portion carrying on its upper extremity a 55 series of downwardly-bent barbs 5.

In the heel-plate at the base of the upwardly-extending spring portion 4 are straps 6 6, which are cut out of said heel portion and are formed integral therewith. Said 60 straps are bent over, as shown in Fig. 2 of the drawings, forming heel connections with a releasing-lever 7, said lever having formed at its lower end an upward extension 8, an operating-handle 9 being formed at the other 65 end thereof. The said heel-plate 3 is apertured, as shown at 10, which is for the purpose of receiving fastening means, and this plate carries a forward extension 11, in which are formed a series of slots 12. 70

The reference-numeral 13 represents a clamp having formed integral therewith a tongue 14, said tongue terminating in a downwardly-bent hook portion 15, the under face of said clamp 13 being provided with guides 16, which 75 are adapted to receive the sides of the extension 11. An upwardly-extending lug 17 is formed on the upper face of the clamp.

The operation of my improved overshoe attachment is as follows: Assuming the clamp 80 is adjusted to conform with the heel of the shoe, the latter is placed in the overshoe, the heel wedging itself between the lug 17 and the upwardly-extending spring portion 4 of the heel-plate. By reason of the downwardly-extending barbs the said spring portion 4 can be easily operated, forcing the upwardly-extending spring portion rearwardly. The points of the barb will then engage the rear portion of the heel, which will serve to retain the 90 shoe in its proper position. When it is desired to remove the overshoe, the handle 9 of the lever 7 is depressed, thereby forcing the upwardly-extending spring-plate rearwardly and releasing the barbs from engagement 95 with the heel of the shoe, and the latter may then be removed in the ordinary manner.

From the foregoing description the many advantages obtained by the use of my improved attachment will be readily apparent 100 and a further detail description is thought to be unnecessary. It will be noted, however, that various changes may be made in the details of construction of my improved attach-

ment without departing from the general spirit of my invention.

Having thus fully described my invention, what I claim as new, and desire to secure by 5 Letters Patent, is—

In a device of the character described, the combination of a heel-plate, an extension formed integral with the front thereof, an upwardly-extending spring portion formed integral with the rear of the heel-plate, a series 10 of barbs formed integral with the upper edge of the spring portion, a pair of straps arranged on the said plate at the front of the spring

portion, a clamp suitably secured to the said extension, an upwardly-extending lug formed integral with the outer end of the said clamp, and an operating-lever secured to the said straps for operating the said spring portion, substantially as set forth.

In testimony whereof I affix my signature 20 in the presence of two witnesses.

FREDRICK MORGESTERN.
